UNITED STATES PATENT OFFICE.

OLE FERGUSON, OF PORTER, MINNESOTA.

STAMP.

1,018,308.

Specification of Letters Patent. Patented Feb. 20, 1912.

Application filed June 14, 1911. Serial No. 633,024.

To all whom it may concern:

Be it known that I, OLE FERGUSON, a citizen of the United States, and a resident of Porter, in the county of Yellow Medicine 5 and State of Minnesota, have invented a new and Improved Stamp, of which the following is a full, clear, and exact description.

My invention relates to stamps, and more particularly relates to egg stamps, and has 10 for an object to provide a stamp so constructed and arranged that it will fit in the hands of the user and as the latter picks up an egg and brings it in contact with the stamp on the palm of his hand, it will make 15 an impression upon the egg to indicate when the egg was gathered or marketed.

A further object of my invention is to provide a structure adapted to conform to the curvature of the egg as it rests in the 20 palm of the hand.

A further object is to provide a stamping device of this character, so arranged that the stamp may be changed at will, to indicate different dates and other data.

With the above and other objects in view, as will more fully hereinafter appear, the present invention consists in certain novel 25 details of construction and arrangements of parts hereinafter fully described, illustrated 30 in the accompanying drawings, and more particularly pointed out in the appended claim.

Reference is to be had to the accompanying drawings, forming a part of this specification, in which similar characters of reference indicate corresponding parts in all the figures, and in which—

Figure 1 is a perspective view of a preferred embodiment of my invention applied 40 to a hand and showing the stamped egg; Fig. 2 is an inside view of my stamp, the parts being laid open; Fig. 3 is a view similar to Fig. 2 but showing the reverse side, an outer flap being broken away to show the 45 type case; Fig. 4 is a transverse sectional view taken on the line 4—4 of Fig. 2 and looking in the direction of the arrow; and Fig. 5 is a perspective view of the type case.

In the several figures, I have shown a hand 50 section 6 adapted to conform to the palm section of the hand and extending along the wrist where it is fastened by means of a wrist band 7 encircling the wrist and fas-

tened in position by means of strap-and-buckle connections 8. The palm portion 6 55 is fastened to the hand by means of a strap-and-buckle connection 9 extending between the thumb and first finger and meeting on the back of the hand. By this construction, the device in no way interferes with the 60 working of the fingers and thumb. The hand portion comprises two superposed layers, the outside layer 10 having a recessed portion 11 into which recessed portion projects the type 12, said type carried on a 65 pad 13, which type is supported in a type case 14. The type case 14 comprises a plate 15, to each end of which is hinged the cover 16, which cover is held in closed position by means of a rod 17 passing through alined 70 beads 18 formed by curling the end of the plate 15 opposite the hinged end. Disposed in the aperture 19 between the alined beads, is the out-curved end 20 of the cover 16. It is seen that this cover fits over the type, 75 holding the same firmly in position, but by withdrawing the rod 17, the cover 16 may be raised to the position shown in Fig. 5 and other type substituted for the type there- 80 in shown. Covering the type case and forming a backing for the under portion, is a second covering piece 21.

While a preferred embodiment of the invention has been described, it is to be understood that many changes could be made 85 in the above construction and many apparently widely different embodiments of this invention could be made without departing from the scope thereof.

It is intended that all matters contained 90 herein in the above description or shown in the accompanying drawings, shall be interpreted as illustrative and not in a limiting sense. It is also to be understood that the language used in the following claims is in- 95 tended to cover the full scope of the invention and is not to be given any narrower construction than the prior art demands, and that materials, sizes and relativities of parts are non-essential, except as called for in the 100 claim.

Having thus described my invention, I claim as new and desire to secure by Letters Patent:

In an egg stamp adapted to be carried by 105 the hand, means fastening said stamp to the

hand, said stamp having an aperture therein, a stamp case, said stamp case having an aperture therein in alinement with the aperture in the stamp, removable type carried by said case and adapted to project through said alined apertures, and a cover to said case adapted to hold said type in position.

In testimony whereof I have signed my name to this specification in the presence of two subscribing witnesses.

OLE FERGUSON.

Witnesses:

GEORGE W. ENGSTROM,
JAC BRYNILDSEN.
